DOUBLE-WALLED TUBULAR HEAT EXCHANGER

BACKGROUND OF THE INVENTION

Double-walled, tubular heat exchangers, more particularly crystallization coolers, in whose interior scraper blades are arranged which abut against the inner wall of the heat exchanger and are secured to a rotatable shaft extending in the axial direction are known per se. They are used, for example, for the continuous cooling of a molten material which is solid at normal temperature, and for converting the melt to a mass of crystals. In order to ensure that the mass crystallizes as uniformly as possible throughout and that flowable or pourable crystals are obtained instead of coherent blocks of crystals, it is necessary to stir the mass round continuously during the cooling and crystallizing operation. The stirring means are usually constructed as scraper blades or helical elements, which has the advantage that at the same time they move the mass forwards through the cooling apparatus.

To dissipate the crystallization heat which is evolved during solidification, a coolant is conducted through the space between the two walls of the heat exchanger which are arranged coaxially one within the other. The coolant may be, for example, water at a suitable temperature or a suitable brine which is appropriately temperature-controlled in accordance with the nature of the material being processed.

Apparatus of this kind are shown for example in German patent specifications Nos. 249,680 and 808,829. These publications also show that the tubular heat exchangers are generally arranged horizontally, and a plurality of such apparatus can be connected in series with one another, the material to be cooled passing through them, for example, in zigzag manner.

When the melt is cooled within the heat exchanger, the heat released is dissipated by conduction. Since the tubular crystallization chamber is cooled from the outside, it is unavoidable that the cooling process proceeds most quickly in the vicinity of the wall, so that in that region a more or less securely adhering layer of crystals forms. This layer of crystals must be continuously removed by means of the scrapers and mixed with the remainder of the mass of crystals.

In the known forms of embodiment of the apparatus dealt with here, the inner surface of the heat exchange tube is continuously scraped, the application pressure of the scraper blades or the helical element being always identical. This has the disadvantage that it is not possible to influence individually the application pressure in accordance with the particular crystallization conditions obtaining.

SUMMARY OF THE INVENTION

The problem underlying the invention is in providing an apparatus wherein the application pressure with which the scraper blades or other scraper means abuts against the inner wall of the heat exchanger, can be adjusted to an optimum value and, if necessary, also individually regulated.

This problem is solved with a double-walled tubular heat exchanger of the type described hereinbefore which is, according to the invention, characterized in that for pressing the scraper blades against or lifting them away from the inner wall of the heat exchanger there are arranged between the blade and the shaft pneumatic or hydraulic adjusting devices whose pressure medium chambers communicate through the interior of the shaft with an external pressure source. This arrangement makes it possible to press the scraper blades more or less strongly against the wall, depending on requirements, or to lift them away from the wall completely if it is not desired to scrape the inner wall. It is also possible with the apparatus proposed to scrape the inner wall only periodically at selectable intervals of time, the intervals being adjusted or preselected, for example, by suitable control apparatus.

A preferred form of embodiment of the apparatus according to the invention is characterized in that the blade holders are mounted to be displaceable in the radial direction of the heat exchanger in the terms of a helical element supported by

the central shaft. The helical element in this form of embodiment has the task of conveying the material axially through the apparatus and at the same time supporting the scraper blades which are radially displaceable.

5 It is particularly advantageous if a plurality of blade holders are arranged in the longitudinal direction of the heat exchanger, each being associated with a pneumatic or hydraulic adjusting device whose pressure medium chambers communicate with the outside individually or jointly through the interior of the shaft. In this way it is possible to scrape with varying application pressure in the various sections of the apparatus, thus permitting optimum utilization of the apparatus and the energy used.

15 It is also proposed to arrange the blade holders which follow one another in the longitudinal direction so that they are offset in each case by 90° relatively to one another, thus achieving the result that the scraping means bear on the inner wall of the heat exchanger in every position, which is advantageous more particularly in the case of apparatus of great length.

20 In order not to scratch the delicate, and in many cases polished, inner surface of the heat exchanger by the contacting helical element sliding during revolution, the helical element can be provided at its outer periphery with cushions of a suitable material, for example polytetrafluoroethylene or the like. These cushions can be in the form of strips which are inserted interchangeably in appropriately shaped extensions on the outer edge of the helical element.

25 The adjusting devices for pressing-on and lifting-off the scraper blades are preferably constructed as closed bellows chambers. The material of which the bellows or diaphragms are produced will depend on the nature of the material being processed in the apparatus, and more particularly on its corrosive properties. But it must also be borne in mind that the fully 30 crystallized pulp subjects the bellows surface to wear, so that this must be as abrasion-resistant as possible. It is most advantageous to use metal bellows for the adjusting devices. It may be advantageous to connect the two end plates of the bellows chambers with telescopically interengaging tubes which 35 are displaceable relatively to one another and which in their lower region comprise radially directed through-flow apertures for the pressure medium.

40 As pressure medium there may be used primarily inert gases, for example nitrogen or the like. Gases have the advantage over liquids that if there are slight leakage losses the material being processed is not fouled. Also they have the advantage that the scraper blades abut elastically against the inner wall of the heat exchanger owing to the compressibility of the gases. On the other hand, when using liquids as pressure transmitting means it is possible to produce relatively high application pressures.

45 In another form of embodiment of the adjusting device according to the invention, this has a cylinder and piston whose pressure medium chambers nearest the shaft communicate with the outside through the interior of the shaft and wherein the chambers nearest the heat exchanger each have a spring, preferably a helical spring subjected to pressure. In this form of embodiment, the scraper blade is pressed by means of the pressure medium against the inner wall of the heat exchanger. At the same time, the spring is also compressed, so that its stored energy is used, when the application pressure is relaxed, to lift the scraper blade off the inner wall of the heat 50 exchanger again.

BRIEF DESCRIPTION OF THE DRAWING

The invention will be explained in more detail hereinafter with reference to the accompanying drawings.

In the drawings:

55 FIG. 1 shows a diagrammatic cross section through a form of embodiment of the apparatus according to the invention;

60 FIG. 2 shows a diagrammatic longitudinal section through another form of embodiment;

65 FIGS. 3 and 4 show fragmentary views on a larger scale from cross sections similar to FIG. 1.

DESCRIPTION OF THE PREFERRED EMBODIMENTS

The heat exchanger shown in FIG. 1 comprises a housing having an outer tube 1 in which an inner tube 2 is arranged concentrically. A hollow shaft 3 is arranged concentrically in said inner tube 2. A tubular chamber 4 is used for conducting a coolant therethrough, and the likewise tubular space 5 for receiving the material to be cooled. The chamber 4 is connected by conduits (not shown) to a coolant source and a coolant discharge conduit. Depending on the nature of the material being dealt with, water may be used as the coolant, being conducted for example in a closed circuit with interposition of a suitable cooling device.

The material to be cooled is introduced into the tubular chamber 5 through means which are also not shown, because they are known, and moved by means of a helical element, that is a conveyor screw 6 which is connected fast to the shaft 3 rotating in the direction of the arrow 7. For the continuous cleaning of the inner surface of the tube 2, there are arranged in the interior of the chamber 5 scraper blades 8 which are supported by blade holders 9. In order to enable the blades 8 to be pressed to a greater or lesser extent against the inner surface of the tube 2, or to be removed entirely from the said surface there are arranged between the blade holders 9 and the shaft 3 hydraulic or pneumatic adjusting devices 10 whose pressure medium chambers 11 communicate with the outside by means of openings 12 to which are attached appropriate conduits 24 extending through the interior 13 of the shaft 3. At the end of the apparatus, these pressure conduits are connected through rotary coupling 25 to controllable pressure medium source 26 adapted to be switched on and off.

In the special form of embodiment shown in FIG. 2, the blade holders 9 are mounted to be displaceable in the radial direction of the heat exchanger in the turns of the conveyor screw 6 supported by the shaft 3. This arrangement makes it possible to dispense with special bearings which would otherwise be necessary if in one constructional form there were no screw 6 to serve as a conveying worm. Advantageously, a plurality of blade holders 9 are arranged one behind the other along the screw 6 in the longitudinal direction of the heat exchanger in such an arrangement that each is offset by 90° relatively to adjacent holders, and each has a pneumatic or hydraulic adjusting device 10 associated with it.

The pressure medium chambers of these adjusting devices can be made to communicate individually or jointly with the outside as described hereinbefore. If the pressure medium chambers communicate with the outside individually, as shown, it is possible for each blade to be pressed individually against the inner wall of the tube 2 or removed therefrom. Each adjusting device 10 is connected by its individual conduit 27, 28 and 29 through coupling 30 to a corresponding pressure source 31, 32 and 33 respectively. These pressure sources may be independently controlled.

In this way the apparatus can be adapted in the optimum manner to the particular purpose in view. The screw 6 is provided at its periphery with U-shaped holding elements 22 in which plastics material strips 23 consisting, for example, of polytetrafluorethylene, are interchangeably set.

FIG. 3 shows an embodiment wherein the adjusting device 10 has a cylinder 14 in which a piston 15 is arranged. The 60

piston is connected by means of a rod 16 to the blade holder 9, so that its movement is transmitted to the blade holder. In the example shown in FIG. 3, the pressure medium chamber 11' is connected, through the opening 12, to the interior 13 of the shaft 3. In the chamber 11'' there is arranged a helical spring 17 which is compressed when pressure medium flows into the chamber 11' and the piston 15 is raised in consequence. As a result, energy is stored in the spring 17 and this energy is used, when the pressure in the chamber 11' is relaxed, to lift the blade holder 9 with the scraper blade 8 away from the inner surface of the wall 2.

In FIG. 4, the adjusting device 10 has a bellows chamber 18 which is arranged between two end plates 19 and 19'. The end plates are connected to telescopically interengaging tubes 20, 20' which are displaceable relatively to one another and comprise radially directed throughflow apertures 21 for the pressure medium. In this case the pressure medium flows from the interior 13 of the shaft 3 into the tube 20' and from there through the apertures 21 into the interior of the bellows 18. In this way easy action on the entire interior of the bellows 18 is ensured, and at the same time it is ensured that the blade holder is guided in stable manner by the telescopically interengaging tubes 20, 20'. This additional guiding of the blade holder at its ends in addition to the guiding mentioned hereinbefore may be advantageous if in one apparatus particularly long blade holders happen to be used.

I claim:

1. A heat exchanger for cooling material by means of a cooling medium, having a tubular housing confining a space for said material to be cooled; said housing having an inner wall and an outer wall, said walls defining a space for said cooling medium, a rotatable shaft coaxially arranged in said housing; scraper blades movably mounted on said shaft and movable into engagement with the inner surface of said inner wall; fluid actuated adjusting means having a chamber for a pressure medium and being arranged between at least one of said blades and said shaft; a source for said pressure medium, said shaft including conduit means connecting said chamber with said source.
2. Heat exchanger according to claim 1, in which said shaft comprises a conveyor screw for conveying said material to be cooled in the direction of the axis of said shaft; said scraper blades being movably mounted on said conveyor screw.
3. Heat exchanger according to claim 2, in which said conveyor screw is provided at its outer edge with outwardly open holding strips and cushion strips inserted into said holding strips.
4. Heat exchanger according to claim 1, in which in the direction of the axis of said shaft, there are arranged a plurality of said scraper blades and a plurality of said adjusting means; said conduit means comprising a single conduit communicating with said adjusting means.
5. Heat exchanger according to claim 1, in which, in the direction of the axis of said shaft, there are arranged a plurality of said scraper blades and a plurality of said adjusting means; said conduit means including conduits separate from each other and each communicating with a single adjusting means said source for fluid pressure medium comprises a plurality of sources, one connected to each conduit.
